UNITED STATES PATENT OFFICE

EARL LEO BILHEIMER, OF BONNE TERRE, MISSOURI, ASSIGNOR TO ST. JOSEPH LEAD COMPANY, OF NEW YORK, N. Y., A CORPORATION OF NEW YORK

FUSE CUTTER

Application filed April 24, 1930. Serial No. 446,880.

The invention relates to a fuse cutter for severing appropriate lengths of fuse for blasting and similar operations from continuous lengths of the fuse material, and which is particularly designed for application to a special form of primer box in which the fuse material is contained, which box is described and claimed in a companion application filed of even date herewith.

10 The cutter constituting the present invention includes a bracket adapted to be mounted on the face of one of the box walls adjacent an opening therein through which the fuse is drawn, said bracket having a guide groove 15 in its upper surface, pendent journal bearings to receive a knife carrying handle, and a longitudinal slot transecting the guide groove in which the knife blade operates with a draw or slicing cut to insure a clean severance of the fuse without crushing or impairing the end of the latter.

The invention is illustrated in the accompanying drawings, in which:—

Fig. 1 is a front elevation of the cutter 25 showing the same mounted on a section of the box wall.

Fig. 2 is a section taken on line 2—2 of Fig. 1.

Fig. 3 is a front elevation of the bracket.

30 Fig. 4 is a plan view of the same.

Fig. 5 is a section on line 5—5 of Fig. 3.

Fig. 6 is a partial sectional elevation of the cutter arm and the knife blade associated therewith.

35 Fig. 7 is a partial edge elevation of the same.

Referring to the drawings, 1 indicates the base of the bracket, which is of substantially inverted U form and is provided with screw

40 receiving openings by means of which the bracket is secured to the wall of a box or other support a. Formed integrally with the base are spaced side arms 2—2, which are preferably inclined upwardly and are connected by a bridge piece 3, in the top of which is formed a transverse guide 4 for the fuse, said guide comprising an inclined upper surface terminating in a shoulder with a substantially semi-circular groove, which latter,

45 50 when the cutter has been applied to the box

support, is slightly above the longitudinal axis of the hole b in the box wall through which the fuse f is fed. Extending longitudinally of the bridge piece 3 and transecting the guide slot or groove 4 is a slot 5, which opens through the bottom of the bridge piece and preferably has an arcuate top wall. Extending below the bridge piece 3 and disposed substantially midway of the same are pendent lugs 6 provided with open slots 7 in alignment with each other, which constitute journal bearings for the knife mechanism and permit the latter being applied or removed from operative position with facility.

55 The knife mechanism comprises a bar of metal 10 preferably having a crank handle 11 secured to its lower end, the upper end being provided with an open slit 12 with an inclined bottom 13, which slit is designed to receive the cutter blade or knife proper, which, as shown, is a relatively thin section of steel 14 having an arcuate and tapered cutting edge 15 and a lower edge which engages the inclined bottom 13 of the slit 12. The upper end of the bar 10 and the blade 15 are provided with registering openings through which is passed, with a driving fit, a journal pin 16, the ends of which are adapted to engage the bearings 7 in the manner and form shown in Figs. 1 and 2, said journal pin also serving to lock the 60 blade 14 rigidly to the end of the bar 10.

70 When the cutter is not in use, the knife bar is removed from its bearings 7 on the bracket and preferably stored in the box on the wall of which the cutter is installed. When the 75 fuse is to be cut into appropriate lengths for application to a primer cartridge, the knife carrying bar is engaged with its bearing 7 by slipping the ends of the pintle 16 into the open slotted brackets 6. To effect the cutting 80 of the fuse into lengths, it is unwound from the coil in which it is disposed, and drawn through the open guide 4 in the top of the bridge piece 3 of the bracket and, when the proper length of the fuse extends beyond the 85 bracket, the knife bar is swung by its crank handle 11, causing the upper part of the blade 14 to traverse the slot 5 in the bracket, and, because of the shape of the cutting edge of the blade and its eccentricity to its pivotal 90 95 100

axis, it effects a slicing cut, severing the fuse clearly and without crushing or marring the same.

What I claim is:

- 5 1. A fuse cutter comprising a bracket having a base to be secured to a support, spaced lateral arms and a bridge piece spanning the ends of said arms, said bridge piece having a fuse guide groove in its top, pendent bearing lugs on its bottom and a longitudinal slot transecting the guide groove, a knife bar having a journal pin engaging the bearing lugs and a blade operating in the longitudinal slot.
- 10 2. A fuse cutter comprising a bracket having a base to be secured to a support, spaced lateral arms and a bridge piece spanning the ends of said arms, said bridge piece having an open sided groove forming a fuse guide in its top, pendent slotted bearing lugs on its bottom and a longitudinal slot transecting the guide groove, a knife bar having a journal pin engaging the bearing lugs and a blade operating in the longitudinal slot.
- 15 3. A fuse cutter comprising a bracket having a base to be secured to a support, spaced lateral arms and a bridge piece spanning the ends of said arms, said bridge piece having a fuse guide groove in its top, pendent bearing lugs on its bottom and a longitudinal slot transecting the guide groove, a knife bar having a longitudinal slit and a transverse perforation in one end, a knife blade mounted in said slit and having a perforation registering with that in the bar, and a journal pin fitting the perforations in the bar and blade; whereby the journal pin is removably engaged with the bearing lugs and the blade operates in the longitudinal slot in the bracket.
- 20 4. A fuse cutter comprising a bracket having a fuse guide groove in its top, journal bearing lugs below the groove and a longitudinal slot transecting said groove, and a handle having a knife blade and a journal pin at one end to be engaged in the longitudinal slot and the bearing lugs respectively.

In testimony whereof I affix my signature.
EARL LEO BILHEIMER.
